ILLINOIS.

JOINT-PACKING STRIP.

1,210,575.

Specification of Letters Patent. Patented Jan. 2, 1917.

Application filed September 6, 1916. Serial No. 118,646.

To all whom it may concern:

Be it known that I, JOHN F. WHITE, a citizen of the United States, residing at Chicago, in the county of Cook and State of Illinois, have invented certain new and useful Improvements in Joint-Packing Strips, of which the following is a specification, reference being had therein to the accompanying drawing.

10 This invention relates to an improvement in joint packing strips and is designed more particularly with a view of providing durable and inexpensive packing strip for application to relatively movable joints such as 15 union joints found in automobile structures, especially the joints which occur between the body and the chassis of such machines. Heretofore it has been customary to pack the joints between the parts of automobiles 20 with a view of preventing squeaking with a felt or rubber substance both of which are somewhat expensive and soon break down and wear out.

The present invention contemplates the 25 formation of a packing strip of a relatively inexpensive canvas or duck material so formed and treated that it will constitute a proper packing having the requisite frictionizing characteristic and pronounced wearing qualities.

30 A further object of the invention is that of the provision of a packing strip for the purpose as above stated which can be made in sheets, contain the proper constituents to 35 render the same waterproof and anti-squeaky or frictional.

In the accompanying drawings, there is shown in Figure 1, somewhat enlarged, a sheet of packing material embodying the 40 invention; Fig. 2 represents a packing strip embodying the invention.

In carrying out the invention, canvas or duck is conveniently employed, and this by preference is cut or woven on the bias leaving a proper selvage edge. Material of this character, as illustrated in Fig. 1, at A is by preference formed with one of its surfaces fleeced or napped. Such material is commonly referred to as napped duck or canvas. 45 The material is immersed, preferably in sheet form, in a tank or container having therein a frictioning material such as asphaltum or what is commonly known as an asphaltum paint.

The material or treating substance is in the 55 first instance thinned by applying or adding thereto a relatively small quantity of a solvent, such as benzine or naphtha, the mass being first heated so that a ready mixture of the solvent with the asphaltum base or material will be quickly effective. In this condition the material is somewhat of a consistency of mixed paint and the canvas or cloth is immersed in the bath and allowed to remain until the same becomes thoroughly 60 saturated with the mixture. The canvas is then removed from the bath, slightly scraped off to remove unnecessary adhering material, after which it is hung up to dry and within a few hours the twill or smooth 65 side of the cloth is dry enough so that the material can be readily handled without sticking. In this condition the nap or fleecy side of the material carries a large percentage of the treating material which is in a 70 tacky or sticky state. The material is now folded upon itself, the fleecy side innermost and is passed between squeezing rolls, thus causing the fleecy surfaces to firmly adhere, 75 leaving the strip of frictionized duck or canvas in a proper condition to serve as a packing strip. The strips may be of any convenient width and are preferably cut in the proper strip formation varying from one quarter to two inches in width and is ready 80 for use.

A strip of this character is found to possess many advantageous qualities, it representing a frictional material which prevents squeaking and constitutes a packing 85 having a certain amount of yieldability. This latter characteristic is produced by the combined fleecy surfaces.

It has been found desirable, for certain purposes, to sever the treated strip in widths 90 substantially twice the width desired for the finished article and then to turn the edges over with the fleecy side innermost until the edges meet at the center of the strip, as shown in Fig. 2 at B. In this position it 100 may be desirable to stitch the edges, as indicated at C dotted lines, Fig. 2, the stitching passing through both faces of the material. In this connection the stitched form is useful in packing the joints between the 105 hoods of automobile engines and the adjacent parts. The material may also be formed to represent what is now known as

"hood lacings", in which instances the strips would be somewhat narrower than those shown in Fig. 2.

In many instances it will be found that 5 the folded strips can be employed, as shown in Fig. 2 of the drawings, without the stitches, the edges of the folded parts being brought close together and the whole subjected to the action of squeezing rolls.

10 It has been found that the packing strips, as above described, serve the purposes of the yielding felt and rubber strips but are much more durable and less expensive. The fleecy characteristic of the material adds the flexibility found in the other types of strips and also serves to bind the folded parts tightly together owing to the superabundance of tacky treated material carried by the fleecy surfaces.

15 I have found that a material composed of substantially equal parts of asphaltum and petroleum residuum is particularly advantageous for use in the production of these strips and have found also that the material 20 known as asphaltum paint is highly desirable. I desire it to be understood however, that I do not wish to be limited to such treating material, the essential characteristic of the invention being represented in the saturated frictionized material and also of a 25 fleeced or woven fabric impregnated with frictionizing material.

Having thus described the invention, what is claimed is:

30 1. A packing strip composed of superimposed layers of a fleeced surface fabric impregnated with frictionizing substance.

2. A packing strip comprising a fleeced surface fabric impregnated with a frictionizing substance folded with the fleeced surfaces innermost and compressed.

3. A packing strip composed of a strip of

fleeced substance impregnated with an adhesive frictionizing substance and folded with the fleecy surfaces innermost.

45

4. A packing strip composed of a folded strip of fleeced fabric impregnated with a substance containing asphaltum.

5. A packing strip comprising a strip of fabric having a fleecy surface, the edges of 50 the fabric being folded inward toward the center of the strip and the strip being impregnated with a water-proof frictionizing substance.

6. A packing strip comprising a strip of 55 fabric having a fleecy surface impregnated with a water-proof tacky substance, the edges of the strip being folded onto the body of the strip with the fleecy surface innermost and pressed together.

7. A packing strip comprising a strip of fabric having a fleecy surface impregnated with a water-proof tacky substance, the edges of the strip being folded onto the body 60 of the strip with the fleecy surface innermost and stitched together.

8. A packing strip comprising a strip of fabric having a fleecy surface impregnated with a water-proof tacky substance, the edges of the strip being folded onto the body 70 of the strip with the fleecy surface innermost and stitched together and to the body.

9. A packing strip composed of laminated strips of fleecy fabric, the fleecy surfaces of which are arranged in contact with each 75 other, the various strips being impregnated with a water proofing substance having a tacky characteristic and pressed together.

In testimony whereof I hereunto affix my signature in the presence of two witnesses. 80

JOHN F. WHITE.
